2,268,979

EXHAUST GAS HEATER

William R. Williamson, Valley Stream, and Felix Saco, Jr., Island Park, N. Y., assignors to The Maxim Silencer Company, Hartford, Conn., a corporation of Connecticut

Application April 5, 1940, Serial No. 328,018

1 Claim. (Cl. 257—229)

The present invention relates to heat reclaiming devices used in connection with the exhaust system of internal combustion motors. Due to the high temperature of the exhaust gases coming from internal combustion motors a very substantial portion of the heat theoretically available from the fuel is wasted, passing out to atmosphere through the exhaust system without being reclaimed in any way. The present invention relates to a device for heating water or other liquid from the exhaust system, the hot water thus produced being used either directly as an intermediate heat carrying agent for any purpose desired, or being converted into steam.

The invention has particular application to stationary engine installations which are generally run for long periods at a steady load. Under these conditions the available temperature in the exhaust gases remains substantially constant, although the requirements of the device to which the reclaimed heat is being furnished may vary widely. To satisfy this condition one object of the present invention is the production of an exhaust operated water heater through which any desired proportion of the exhaust gases may be passed or which may be shut off entirely from the exhaust gases without impeding the flow of the latter. Since the device is intended to be used on stationary internal combustion engines which frequently use a low grade of fuel it is necessary to provide some way in which sooty deposits may be removed from the heating system so that the efficiency of the latter will not be materially impaired. It is, therefore, an additional object of the invention to provide an exhaust operated water heater which may be cleaned without necessitating the shutting down of the power plant to which it is connected. A further object of the invention is to provide a heater of this general character with a valve mechanism which will be substantially unaffected by the pulsating character of the exhaust gas stream. Additional objects will appear from the following description and claim.

Referring to the drawings:

Fig. 1 is a vertical section through a heating device constructed in accordance with the invention, taken on line 1—1 of Fig. 3;

Fig. 2 is a section on line 2—2 of Fig. 1;

Fig. 3 is a section on line 3—3 of Fig. 1;

Fig. 4 is a detail of certain valve operating mechanism; and

Fig. 5 is a detail showing the valves in a position closing off the flow of exhaust gases through the heater.

In its preferred form the device comprises an elliptical upper section 10 having a circular flange 11 at its lower end to which a flange 12 on a lower cylindrical portion 13 may be attached as by bolts 14. Inlet and exhaust connections 15 and 16 are attached to the ends of the elliptical section and the latter is provided with internal horizontal and vertical partitions 18 and 19, respectively, by which it is divided into an inlet compartment 20 and an outlet compartment 21. Accessibility to these chambers is provided through a cover 22 removably held in place as by bolts 23.

The horizontal partition 18 is formed with an opening 25 opening into a lower chamber 26 which communicates with the interior of the cylindrical portion 13. The partition is also provided with a second opening 27 in which is fixed a hollow tubular member 28 extending nearly to the bottom of the cylindrical member 13 and having its lower end open. Valve structure to be described later is provided so that the gases may pass through the chambers 20 and 26 into the interior of the cylindrical member 13 and then upwardly through the tube 28 into the outlet chamber 21. In this travel the gases flow around a heating coil conventionally shown at 29 and preferably having heat conducting fins 30 formed along its length, only a few of these fins having been shown in the drawings for purposes of simplicity. The ends of the heating coil pass out through the upper member 10 through suitable connections 31 and 32 and the flow of water through them is preferably in a direction opposed to that of the exhaust gases.

The partition 19 is provided with a single opening 35 and is suitably machined adjacent this opening so as to provide two opposite valve seats 36 and 37. The partition 18 is similarly machined adjacent the openings 25 and 27 so as to form valve seats 38 and 39. A pair of valve members are provided which may be oscillated from the position shown in Fig. 1 to that shown in Fig. 5. The valve members carry valve plates 40 and 41 which in the first position close the opening 35, and valve plates 42 and 43 which in the second position close the openings 25 and 26. In the position closing the opening 35 the valves block off the exhaust stream and force it to pass through the heating chamber 13. The gas stream is of a pulsating character and were a single valve to be employed there would be difficulty due to the valve being pushed alternately in opposite directions, causing chatter and leakage. The tubular valve structure shown always

has one valve in a position to be pressed more tightly against its valve seat by the pulsations in the gas stream no matter in which direction these pulsations are acting. In the position of Fig. 5 the valves block off both entrances in the lower chamber and permit the exhaust gases to flow without obstruction through the opening 35. In the latter position the heating chamber is completely shut off from the exhaust gas stream and the casing 13 may be removed and the heating coil and interior of the chambers cleaned without necessitating interruption of the operation of the engine.

In order to avoid the necessity for great accuracy in the machining of the valve seats and to prevent leakage due to warping of the metal surfaces on account of the high temperature of the exhaust gases, the valves are preferably made of a special construction indicated in detail in Figs. 1 and 2. Each valve member is provided with an operating shaft 45 upon which is pinned a pair of arms 46 carrying a transverse rod 47. The two plates 40, 42 or 41, 43 as the case may be, are jointly secured to a bearing member 48 free to turn on the rod 47 so that as the arms 46 are swung into one or the other of their valve closing positions the valve plates may be free to adjust themselves to the surface of the valve seat. In order to avoid too great freedom of movement, however, a pair of lugs 49 are preferably secured to each rod 47 and extend between the valve plates as best shown in Fig. 1 so as to limit the oscillation of the latter about the rod 47.

The operating shafts 45 extend outwardly through stuffing boxes 50 and, as best shown in Figs. 3 and 4, each have an arm 51 secured thereto. Links 52 are pivoted to the arms 51 at 53 and are pivoted at 54 to a rod 55 slidable vertically in ways 56. By raising and lowering the rod 55 the arms 51 may be rocked and will be held yieldably in either extreme position by a spring 57 which is caused to pass to one side or the other of the line of centers of the shafts 45 by the rocking of the arms. The rod 55 is preferably provided with a handle 58 and with a locking screw 59 so that it may be held as desired in any intermediate position allowing only

a fraction of the exhaust gases to pass through the heating unit.

What we claim is:

An exhaust gas heater comprising a casing member providing a through channel normally adapted for horizontal mounting in the exhaust line of an internal combustion engine, inlet and outlet connections to connect said channel to the exhaust line of an internal combustion engine, a second member providing a depending substantially cylindrical heat exchanger chamber having its upper end wall and a portion of its side wall formed integrally with a side wall of the through channel and a removable cap forming the lower end wall and the rest of the side wall of the chamber, a conduit for fluid to be heated mounted in the chamber with substantially its entire heat exchanging surface located within that portion of the chamber which is formed by the cap, an apertured partition extending transversely of the through channel across the normal path of gases through the channel and intermediate the inlet and outlet connections for said channel, the side wall of the through channel having an auxiliary aperture for communication therethrough between the inlet side of said partition and the heat exchanger chamber, a conduit on the outlet side of the partition extending from the side wall of the through channel axially through the exchanger chamber to a point adjacent the lower end wall, said auxiliary aperture and conduit as well as the passageway for gases in passing from one to the other through the chamber being dimensioned to present a pathway for exhaust gases substantially equal in cross-section to at least the minimum cross-section of the through channel, and valve means in the through channel, one on each side of the partition and arranged to seat on the opposite faces of the partition and close the aperture therein or alternatively to seat on the side wall of the through channel and close communication between the through channel and the heat exchange chamber.

CERTIFICATE OF CORRECTION.

Patent No. 2,268,979.

January 6, 1942.

WILLIAM R. WILLIAMSON, ET AL.

It is hereby certified that error appears in the printed specification of the above numbered patent requiring correction as follows: Page 2, second column, line 10, in the claim, after "second" insert --casing--; and that the said Letters Patent should be read with this correction therein that the same may conform to the record of the case in the Patent Office.

Signed and sealed this 10th day of March, A. D. 1942.

Henry Van Arsdale,
Acting Commissioner of Patents.
